UNITED STATES PATENT OFFICE.

JOSEPH C. McALEXANDER AND BENJAMIN H. THOMAS, OF CHARLOTTESVILLE, VIRGINIA.

LUBRICATING-PLUG.

SPECIFICATION forming part of Letters Patent No. 628,019, dated July 4, 1899.

Application filed April 7, 1898. Serial No. 676,802. (No model.)

To all whom it may concern:

Be it known that we, JOSEPH C. McALEXANDER and BENJAMIN H. THOMAS, citizens of the United States, residing at Charlottesville, 5 in the county of Albemarle and State of Virginia, have invented certain new and useful Improvements in Lubricating-Plugs; and we do declare the following to be a full, clear, and exact description of the invention, such 10 as will enable others skilled in the art to which it appertains to make and use the same.

The invention has relation to lubricating-plugs for steam-chests of engines, more particularly to engines of the locomotive type.

15 The object of the invention is to provide means whereby the oil may be more regularly supplied to the chest while the locomotive is working, and especially at high pressure, without the necessity of shutting off the engine.

20 With this object in view the invention consists in certain features of construction and combination of parts hereinafter fully described and claimed.

25 The accompanying drawing illustrates our invention in vertical section, showing one end connected to a steam-chest and the other end connected to the pipe leading from the lubricator, which lubricator is arranged in the cab 30 of the locomotive.

As the steam-chest and the lubricator form no part of our invention, a further description of the same is not deemed necessary. Hence we will now proceed to describe our invention, 35 referring to the other parts shown only incidentally.

1 denotes a steam-chest, and 2 the pipe leading from the lubricator (not shown) located in the cab of the locomotive.

40 3 denotes the plug-casing, which consists of the body portion 4, having an enlarged condenser-chamber 5 at its lower end and a reduced chamber 6 at its upper end. The outer side of the casing is provided with 45 screw-threads that engage the screw-threaded aperture formed in the valve-chest, and a clamping-nut 7 is employed for the purpose of clamping the parts in position. The interior of the casing, at its lower end, is provided with screw-threads that receive the screw-threads 8 of the reducer, the upper end of

which is conical and terminates in a sharp point 9. This reducer is centrally bored, as shown at 10, and the upper end of this bore is contracted to reduce the opening to about 55 three one-hundred-and-twenty-eighths of an inch, more or less, to measure out or restrict the flow of the oil, which may freely pass downward therethrough, and the longitudinal bore, by virtue of its considerable length and 60 because it has a slightly larger diameter than the contracted portion, will permit the oil to flow freely to the parts to be lubricated without allowing the steam to interfere with the downward movement. Assuming the bore to 65 be of uniform dimensions throughout, the oil might be prevented from passing downward if said bore were only as large as the contracted portion, and if said bore contained no contracted portion the oil would be delivered in undesirable quantities. The conical end of the reducer extending up through the lower end of the casing forms a trap 11, so that impurities in the oil, such as sediment and foreign matter, will not pass through the 70 bore of the reducer to the valve-seats in the steam-chest.

12 denotes a clamping-nut secured to the upper end of the casing 3 and by means of which the end of the lubricator-pipe is attached to the casing.

75 The operation of the device is as follows: The casing being attached to the lower end of the lubricator-pipe and the lubricator in the cab of the locomotive being set to allow oil to drop through said pipe and a pressure 80 maintained in said pipe equal to or greater than the back pressure from the steam-chest, since steam is freely admitted through the upper end of said pipe by an equalizing-passage in the lubricator, it is evident that the specific gravity of the oil will cause it to drop 85 through the steam in said pipe and pass out through the bore of the reducer. The upper end of this bore is contracted or reduced to 90 such an extent that the steam passing therethrough from the steam-chest will not in the least interfere with the passage of oil downward through said bore even while the engine 95 is at work under high pressure. This is the very gist of our invention.

100 By the employment of our device the oil is

fed regularly and constantly, so that the valves are properly lubricated and no oil lost.

Changes in the form, proportion, and the minor details of construction may be resorted to without departing from the spirit or sacrificing any of the advantages of this invention.

Having thus described our invention, what we claim, and desire to secure by Letters Patent, is—

10. The combination of a casing having an enlarged condensing-chamber 5 communicating with the chamber 6, and a reducer secured to the lower end of the casing and having a conical end projecting upward quite near to

the chamber 5 to form the trap, said reducer 15 having a longitudinal bore, the upper end of which is contracted, and means for attaching the casing at one end to the discharge-pipe of the steam-lubricator and at the other end to the steam-chest, substantially as set forth. 20

In testimony whereof we have hereunto set our hands in presence of two subscribing witnesses.

JOSEPH C. McALEXANDER.
BENJ. H. THOMAS.
